CLAIM

The ornamental design for a garden hose reel concealed in a barrel, as shown and described.

DESCRIPTION

FIG. 1 is a perspective view of a garden hose reel concealed in a barrel, showing my new design;

FIG. 2 is a perspective view of the invention, illustrated with a hose on the reel and with a top of the barrel removed;

FIG. 3 is a perspective view of the invention, illustrated without the hose and with the top of the barrel removed;

FIG. 4 is a front elevational view of the invention;

FIG. 5 is a rear elevational view of the invention;

FIG. 6 is a right-side elevational view of the invention;

FIG. 7 is a left-side elevational view of the invention;

FIG. 8 is a top plan view of the invention; and,

FIG. 9 is a bottom plan view of the invention.

The broken lines showing a hose in the figures are included for the purpose of illustrating the invention in use, and form no part of the claimed design.
